[57] CLAIM

The ornamental design for a carrier for a paint can or the like, as shown and described.

DESCRIPTION

FIG. 1 is a top, front and side perspective view of a carrier for a paint can or the like showing my new design;

FIG. 2 is a top, front and side perspective view thereof, shown with the mounting part positioned angularly from that shown in FIG. 1;

FIG. 3 is a top plan view thereof;

FIG. 4 is a front elevational view thereof;

FIG. 5 is a left side elevational view thereof;

FIG. 6 is a bottom plan view thereof; and

FIG. 7 is a rear elevational view thereof.

The broken line showing of belt and straps in FIG. 1 is for illustrative purposes only and forms no part of the claimed design.
